UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed December 6, 1923. Serial No. 678,792.

To all whom it may concern:

Be it known that I, SNOWDEN B. REDFIELD, a citizen of the United States, and a resident of Easton, county of Northampton, and 5 State of Pennsylvania, have invented a certain Compressor Unloader, of which the following is a specification, accompanied by drawings.

This invention relates to compressor unloaders but more particularly to unloading mechanism which may be manually or automatically operated to unload the compressor cylinder so that the compressor may continue to be operated without accomplishing 10 useful work, or a reduced amount of useful work.

It is often desirable to start a compressor under a no-load condition especially if the compressor is driven by an electric motor 15 or if the discharge line pressure is high. In accordance with the present invention, means are provided for manually unloading the compressor cylinder by holding one or more inlet valves open, so that the fluid drawn 20 into the compressor cylinder on the suction stroke of the compressor piston will be forced out to atmosphere on the compression stroke when both inlet valves are held open, or a reduced amount of pressure fluid 25 forced into the discharge line when one valve is held open. This manual unloading may be accomplished by turning a handle which causes fingers to bear against and unseat the compressor valve.

30 The present invention also contemplates means whereby the unloading of the compressor may be automatically governed by the receiver pressure, so that when the pressure therein has reached a certain predetermined point partial or complete unloading 35 may automatically occur.

One of the objects of the present invention is to enable manual unloading of a compressor to be accomplished by turning or rotating a handle to cause members such as 40 fingers to bear against and unseat a compressor valve.

Another object of the invention is to produce a compressor unloader adapted to be 45 either pneumatically or manually operated, which may be cheaply manufactured and is readily and conveniently applicable to a compressor in an assembled condition.

A further object of the present invention is to improve upon compressor unloaders 55 with the view of making them more rugged, reduce the number of parts, facilitate their assembly in a compressor cylinder, and effect a fluid tight construction.

Further objects will hereinafter appear 60 and the invention consists of certain combinations of elements and features of construction particularly set forth in this specification, defined in the appended claims, and shown in the accompanying drawings, in 65 which—

Figure 1 is a diagrammatic elevation partly in vertical section of a compressor unit,

Figure 2 is an enlarged vertical sectional 70 view of the compressor unloader shown in Figure 1.

Figure 3 is a view similar to Figure 2 showing the compressor valve held open,

Figure 4 is a horizontal sectional view 75 taken on the line 4—4 of Figure 3, and

Figure 5 is a horizontal sectional view taken on the line 5—5 of Figure 3 looking in the direction of the arrows.

Referring to the drawings, the compressor A is formed with a casing B and cylinder wall C, in which a piston D having a piston rod E is adapted to reciprocate, being driven from any suitable source of power. The compressor cylinder wall C is provided with suitable inlet valves F which are in communication with the intake conduit G, and suitable discharge valves H which in this instance are in communication with a receiver J through the discharge line K. An inlet valve mechanism preferably comprises a valve seat L, and guard O, between which is clamped a plate valve P, by means of a bolt Q and nut R. It is to be understood, however, that any suitable valve mechanism may be employed without departing from the scope of the present invention.

In accordance with the present invention, a cover S having a hollow boss U, is preferably secured to the compressor casing B by stud bolts T. A cylinder V is located in the hollow boss U and is preferably provided with extensions W, terminating in an annular ring W', adapted to bear against the valve seat L for holding the valve mechanism in place in the compressor cylinder C.

An external annular flange X is in this instance formed on the cylinder V and limits the inward movement of the cylinder in the hollow boss U in the assembly of the parts.

- 5 A hollow piston Y preferably having a suitable piston ring Z is slidably mounted in the cylinder V and is in this instance formed with a threaded end portion a, on which is screwed a collar b. Instead of
- 10 threading the collar b, a diagonal slot may be formed therein adapted to cooperate with a pin or lug on the end portion a of the cylinder. A plurality of fingers c are preferably formed integrally with the collar b
- 15 and extend outwardly therefrom for unseating the compressor valve, as will be hereinafter described. In order to hold the piston Y normally in its inward position, in the cylinder V and to hold the fingers c
- 20 normally away from the plate valve P, a coil spring u is in this instance interposed between the inside of the piston Y and the valve mechanism F.

Opposed lugs, preferably a pair of lugs d are in this instance formed on one end of the piston Y, and a stem e is preferably provided with a cross pin f, which is adapted to bear against the lugs d. The stem e, in this instance, extends through a plate g which is suitably secured to the cover S by stud bolts h, and a suitable handle j on the stem e enables the stem to be readily manipulated. A packing gland k and packing o in this instance surround the stem e and serve to prevent the escape of pressure fluid from a chamber p which is formed between the plate g and the inner end of the piston Y. A suitable packing q is in this instance interposed between the plate g, cover S and cylinder V, and pressure fluid is prevented from escaping therebetween by tightening the plate g on the cover S. Suitable packings r are preferably interposed between the cover S and compressor casing B, and valve seat L and compressor cylinder C, for maintaining a tight joint between the parts. By constructing the unloading mechanism as described, considerable flexibility between the parts is obtained and the cover S, plate g, and casing B can be secured firmly together to effect an efficient fluid tight connection. This construction makes this device applicable not alone to air compressors, but to other analogous types of machines as an ammonia or other gas compressor.

In this instance a coil spring s is located between the cross pin f and plate g and permits the stem e to move a slight distance inwardly in the plate g when the plate is being secured to the cover S, so that breakage of the cross pin f will be prevented in the assembly of the parts. A collar e' on the stem e limits the inward movement of the stem in the plate g.

65 In the operation of the unloader so far

described, by turning the handle j to rotate the stem e in a counter-clock-wise direction, with the cross pin f bearing against the lugs d, the piston Y will be unscrewed from the collar b, because the fingers c are held from rotation by the webs t in the valve seat L, as indicated in Figure 4. The fingers c will accordingly be moved outwardly from the threaded end portion a and the piston Y will press inwardly in the cylinder V against the plate g. As the fingers c move outwardly from the cylinder V they will bear against and unseat the plate valve P, and the pressure fluid drawn into the compressor cylinder on the suction stroke of the compressor piston D will be forced out to atmosphere upon the compression stroke of the piston when both inlet valves are open, and no pressure fluid will be forced into the discharge line K. By turning the handle j in a clock-wise direction, the collar b will be moved inwardly on the threaded end portion a and the fingers c drawn away from the compressor valve P, and the compressor is permitted to reload with the inlet valves operating normally.

Suitable automatic means is provided for unseating the compressor valve P and in this instance, the plate g is provided with a passage v, which is adapted to communicate with a receiver J by suitable piping w. In order to regulate the passage of air from the receiver J to the chamber p in rear of the piston Y, a suitable auxiliary valve x is connected to the piping w and is adapted to be adjusted to the pressure desired in the receiver J. As soon as the pressure in the receiver J has reached a desired point, as controlled by the auxiliary valve x, pressure fluid will be admitted through the piping w to move the piston Y in order that the fingers c may bear against and unseat the plate valve P. As soon as the pressure in the receiver J has dropped sufficiently, the auxiliary valve x will shut off the passage of fluid from the receiver J to the chamber p, and the spring u will return the piston Y to its normal position, and thereby permit the plate valve P to function normally.

In order to obtain partial unloading, one of the auxiliary valves x may be set to operate at one pressure in the receiver and the other auxiliary valve may be set to operate at a higher pressure. In this manner, when the receiver pressure reaches a certain point, one of the auxiliary valves will operate to admit pressure fluid to one of the unloaders, but the other unloader will not be brought into operation, and as a result the compressor will work at only half load. Further increase in pressure in the receiver will bring the other auxiliary valve into operation, and complete unloading will occur. It is to be understood that any suitable auxiliary valve may be employed so that air

will be automatically supplied to the unloading device, after the receiver pressure has reached a predetermined point.

I claim:

- 5 1. A compressor unloader comprising in combination with a compressor cylinder and plate valve mechanism in the wall of said cylinder, a cover adapted to be secured to the compressor cylinder casing, a cylinder in said cover having means for holding the valve mechanism in place in the compressor cylinder, a piston in said last mentioned cylinder having a threaded end portion, a collar on said threaded end portion provided with fingers adapted to bear against the plate valve, opposed lugs on one end of the piston, a plate secured to the cover, a stem extending through said plate and provided with means for engaging said lugs, and means for rotating said stem, whereby rotation of the stem in one direction causes the fingers to bear against and unseat the plate valve.
- 10 2. A compressor unloader comprising in combination with a compressor cylinder and a plate valve mechanism, a cover adapted to be secured to the compressor cylinder casing, a cylinder in said cover having means for holding the valve mechanism in place in the compressor cylinder, a piston slidable in said last mentioned cylinder having a threaded end portion, a collar on said threaded end portion provided with fingers adapted to bear against the plate valve, a spring bearing against the valve mechanism at one end and the inside of the said piston at the opposite end, opposed lugs on the piston at one end thereof, a plate secured to the cover, packing between the plate, cylinder and cover and forming a seal therebetween, a stem in said plate, and means carried by one end of the stem adapted to bear against said lugs, and means for rotating said stem whereby rotation of the stem in one direction causes the fingers to bear against and unseat the plate valve.
- 15 3. A compressor unloader comprising in combination with a compressor cylinder and a plate valve mechanism, a cover adapted to be secured to the compressor cylinder casing, a cylinder in said cover having extensions terminating in a ring for holding the valve mechanism in place in the compressor cylinder, a piston slidable in said last mentioned cylinder having a threaded end portion, a collar on said threaded end portion provided with fingers adapted to bear against the plate valve, a spring bearing against the valve mechanism at one end and the inside of the said piston at the opposite end, opposed lugs on the piston at one end thereof, a plate secured to the cover, packing between the plate, cylinder and cover for preventing the escape of pressure fluid therebetween, a stem extending through said plate, a cross pin carried by one end of the stem adapted to bear against said lugs, means for rotating said stem whereby rotation of the stem in one direction causes the fingers to bear against and unseat the plate valve, and a spring interposed between said pin and plate adapted to prevent breakage of the pin in assembling of the parts in a compressor.
- 20 4. A compressor unloader comprising in combination with a compressor cylinder and a plate valve mechanism, a cover secured to the compressor cylinder casing, a cylinder in said cover having extensions terminating in a ring for holding the valve mechanism in place in the compressor cylinder, a piston slidable in said last mentioned cylinder having a threaded end portion, a collar on said threaded end portion provided with fingers adapted to bear against the plate valve, a spring bearing against the valve mechanism at one end and the inside of the said piston at the opposite end, opposed lugs on the piston at one end thereof, a plate secured to the cover, packing between the plate, cylinder and cover for preventing the escape of pressure fluid therebetween, a stem extending through said plate, a cross pin carried by one end of the stem adapted to bear against said lugs, means for rotating said stem whereby rotation of the stem in one direction causes the fingers to bear against and unseat the plate valve, and automatic means for pneumatically operating said piston to unseat said plate valve.

In testimony whereof I have signed this specification.

SNOWDEN B. REDFIELD.
